UNITED STATES PATENT OFFICE.

JOHN L. PRATT, OF DETROIT, TEXAS.

FOOT-REST FOR SCHOOL-DESKS.

1,216,492.

Specification of Letters Patent. Patented Feb. 20, 1917.

Application filed May 27, 1916. Serial No. 100,280.

To all whom it may concern:

Be it known that I, JOHN L. PRATT, a citizen of the United States, residing at Detroit, in the county of Red River and State 5 of Texas, have invented certain new and useful Improvements in Foot-Rests for School-Desks, of which the following is a specification, reference being had to the accompanying drawings.

10 This invention relates to foot rests for school desks and has for its primary object to provide a simply constructed and convenient device which may be readily applied to the ordinary school desk to support the 15 feet of the scholar in a comfortable position above the floor surface.

It is another object of my invention to provide an adjustable foot rest for school desks which can be readily raised and supported in an elevated position when it is desired to sweep or clean the floor beneath the desk.

20 It is a further general object of the invention to provide a device for the above purpose which is very strong and durable and may be manufactured at relatively small cost.

25 With the above and other objects in view, my invention consists in the novel features 30 of construction, combination and arrangement of parts to be hereinafter more fully described, claimed and illustrated in the accompanying drawing, in which,

35 Figure 1 is a perspective view illustrating my improved foot rest applied to a common type of school desk;

Fig. 2 is an enlarged vertical sectional view showing the foot rest disposed in its raised inoperative position;

40 Fig. 3 is an enlarged horizontal sectional view; and

Fig. 4 is a fragmentary perspective view showing the foot rest applied to another construction of desk.

45 Referring in detail to the drawing, 5 designates the desk proper which is suitably mounted and supported upon the end frames or standards 6. In Figs. 1 to 3 of the drawing, I have illustrated means for 50 attaching foot rest bearings or supports to the desk standards. Each of these bearings consists of a circular plate or disk 7 which is adapted to be secured to the metal straps or bars, indicated at 8. The disk 7 is provided with a central bearing opening and the bars 8 with similar openings to coincide

or register therewith. These bars are also secured to the disk, adjacent to its edge, by means of the rivets or bolts 9, the extremities of the bars projecting in parallel relation beyond the edge of the disk. In applying the bearings, the spaced ends of the bars 8 are engaged upon opposite sides of the spaced vertical bars of the frames or standards 6, as clearly shown in Fig. 3 of the drawings. Openings may be drilled through these frame bars and the bars 8 to receive suitable fastening bolts, or if the frames or standards 6 are of such construction that the bolt receiving openings cannot be provided therein without weakening the frame, clamping bolts such as shown at 10, may be disposed through openings in the extremities of the bars 8, and the projecting ends of said bars tightly clamped to the frame.

A horizontal rod 11 has its ends journaled in the central openings in the disks 7, and hanger arms 12 are fixed at one of their ends to the rod 11 adjacent to the inner faces of the disks 7. The other ends of these hanger arms are provided with the flanges 13, and to these flanges the opposite ends of the foot board 14 are securely fixed.

Upon the inner face of each disk 7 and immediately below the bearing opening 85 therein, a radially extending shoulder 15 is formed, and above the bearing opening a second stop shoulder 16 is formed upon the face of the bearing disk, said latter shoulder being also radially disposed and extending at 90 an angle with respect to the shoulder 15.

When the hanger arms 12 upon which the foot board 14 is mounted, are disposed in their normal pendant positions, the rear edges of said arms abut against the shoulders 15 so that the swinging movement of said arms and the foot board in a forward direction beneath the desk is thereby limited. It is a well known fact that the air currents above the floor surface are several degrees 100 warmer than the floor surface itself, and the foot board 14, in its normal position, is spaced above the floor surface so that the scholars' feet, when disposed upon said board, will not be in contact with the relatively cold surface of the floor. Thus, the feet will be supported in a comfortable position and not be subjected to the cold air drafts in immediate juxtaposition to the 105 floor surface. When it is desired to sweep or clean the floor beneath the desk, the foot rest 14 may be swung upwardly by the

broom to the position indicated in Fig. 2, such movement being limited by the engagement of the hangers 12 against the stop shoulders 16. Thus, the foot board is supported immediately beneath the bottom wall of the desk and entirely out of the way, so that the floor surface beneath the desk can be properly swept or cleaned.

In Fig. 4 of the drawing, I have illustrated the bearing plates or disks 7' integrally formed or molded with the end frames or standards 6 of the desk. These bearing disks are provided with central openings so that it is only necessary to mount the ends of the horizontal rod 11 within said openings and then apply the hanger arms 12. It will be noted, of course, that when the rod 11 is inserted in position, the ends thereof are also engaged through the ends of the hanger arms 12 and said arms fixed to the rod by set screws or other suitable means. If desired, however, the ends of the rod 11 may be fixed in the disks or plates 7 and the hanger arms loosely engaged upon the rod for turning movement, as will be readily understood. In the latter construction, the inner faces of the disks or plates 7' are, of course, provided with the stop shoulders, as above described.

From the foregoing description, taken in connection with the accompanying drawing, the construction, manner of operation and several advantages of the invention will be clearly and fully understood. The device, while exceedingly simple, is of great convenience and serviceability in practical use and is so constructed that the same can be readily applied to the ordinary type of school desk now in common use without necessitating any material alterations therein.

While I have shown and described the preferred form, construction and arrangement of the several elements, it is to be understood that the same is susceptible of considerable modification therein and I, therefore, re-

serve the privilege of adopting all such legitimate changes as may be fairly embodied within the spirit and scope of the invention as claimed.

Having thus fully described my invention, what I desire to claim and secure by Letters Patent is:—

1. The combination with a desk including end frames, of a bearing on each of said end frames, a horizontal rod journaled at its ends in said bearings, hangers mounted upon the ends of said rod, a foot board fixed to the free ends of said hangers, each of said bearings being provided on its inner face with stop shoulders to limit the swinging movement of the hangers and the foot board to a pendant position or to an elevated inoperative position.

2. The combination with a school desk including end frames, of bearing disks, means for clamping the bearing disks upon the respective end frames, a horizontal rod journaled at its ends in the bearing disks, each of said disks being provided upon its inner face with a radially disposed stop shoulder in vertical alinement with the bearing opening of the disk and also with the second stop shoulder above the bearing opening and at one side thereof, hangers fixed at one of their ends to said rod, a foot rest secured to the other ends of the hangers, the movement of the hangers in one direction being limited by the first named shoulders on the bearing disks when the foot is in its proper raised position, and the last named shoulders limiting the swinging movement of the hangers in an opposite direction when the foot rest is elevated to an inoperative position.

In testimony whereof I hereunto affix my signature in the presence of two witnesses.

JOHN L. PRATT.
